EARL H. SHERBONDY, OF CLEVELAND, OHIO.

NOZZLE-RING.

1,310,675.

Specification of Letters Patent. Patented July 22, 1919.

Application filed April 8, 1918. Serial No. 227,831.

To all whom it may concern:

Be it known that I, EARL H. SHERBONDY, a citizen of the United States, residing at Cleveland, in the county of Cuyahoga and State of Ohio, have invented certain new and useful Improvements in Nozzle-Rings, of which the following is a specification.

This invention relates to a nozzle ring for a turbine and to a method of making same.

10 It is an object of the invention to provide a one piece nozzle ring, having a body portion which serves as means for mounting the ring as a whole. The nozzle ring in question, is intended and adapted to be used 15 in connection with a gas operated turbine of a type shown in my co-pending case, Serial No. 224892, filed March 26, 1918.

Other objects and advantages will appear as the description proceeds.

20 Referring now to the drawings, in which similar reference characters indicate similar parts, Figure 1 is a side view partly in section, showing the nozzle ring in position in a turbine casing; Fig. 2 is a side view of 25 the blank at one of the stages of manufacture, Fig. 3 is a sectional view on an enlarged scale of the same; Fig. 4 is a development of the edge of the nozzle ring after the slots have been cut; Fig. 5 is a view 30 on line 5—5 of Fig. 4, Fig. 6 is a view similar to Fig. 4 at a later stage of manufacture; Fig. 7 shows the nozzle ring filled with a soft alloy, Fig. 8 shows the nozzle ring after profiling; Fig. 9 is a front view of the 35 finished nozzle ring and Fig. 10 is a view, partly in section and partly in perspective of the same.

The first stage of the operation of making the one piece nozzle ring, is to take a thick-walled metal tube of a material which will 40 withstand the high temperatures met with in a gas operated turbine.

The length of this tube may be substantially equal to the line A, B, Fig. 3, and the 45 thickness of said tube may be substantially equal to line A D, Fig. 3. The excess metal is then cut away, leaving a comparatively thick end portion 1, the annular portion 2 and an upturned portion 3. It should be 50 mentioned in this connection, that Fig. 3 shows a section through an upper wall of the tube.

The end portion 1 is now undercut as at 4 all the way around, so that a portion will 55 overhang this cut.

The next stage in making the nozzle ring is to cut the slots in the portion 1. These slots designated S, are milled in the edge of the end portion 1 in such a manner that the slots S are helical with respect to a longitudinal axis of the original tube, that is to say, the longitudinal axis of the annular portion 2. The cutting of these slots leaves the blades 5 outstanding from the base of the portion 1, it being evident that the 60 blades 5 will also be helical with respect to the axis of the annular portion 2.

During the said milling operation, the work is fed longitudinally, that is, in a direction parallel to the axis of the portion 2, 70 a distance A F, equal to the width of the portion 1. At the same time, the work is rotated about the axis of the annular portion 2 an amount equal to the distance G H, Fig. 4; the milling cutter during both of 75 these motions, while itself rotating, does not move otherwise. The resultant of these two motions causes a helical slot to be cut, which in the development in Fig. 4, appears as a diagonal slot. It should be understood, however, that the body of each slot S, is everywhere equidistant from the 80 axis of the portion 2, that is to say, it winds helically around said axis.

It will now be apparent that portions 5' 85 of the blades 5, to the right of the line 4' 4', representing the inner edge of the undercut portion 4, will overhang said undercut portion, as shown in Fig. 5. The next stage in the making of the nozzle ring is to 90 bend these overhanging portions 5' toward the axis of the portion 2, as shown in Fig. 6. The gases are intended to pass through the nozzle ring in a direction shown by the arrows in Fig. 6. The purpose of the just- 95 mentioned bending, is to change the direction of the opening of the slots S, so that the gases that are going to operate the turbine will be more readily taken into the slots S.

This bending operation can be carried 100 out in any desired manner and as a matter of practice, it is accomplished by first heating the portions 5' in an oxy-acetylene flame to a sufficiently high temperature, then bending them as shown in a suitable jig. Only 105 the parts 5' of the blades 5, overhanging the undercut portion 4, are bent, the purpose of the slot 4 being to permit this bending.

The nozzle ring is intended to be located 110

in turbine casing 6, as shown in Fig. 1 and the outer edge of the nozzle ring must be shaped to provide a proper gas tight seat for the diaphragm 7, located in the casing 6. The casing 6 carries inlet and exhaust pipes 8 and 9, and the diaphragm 7 is within the casing 6, between these two pipes. The annular portion 2 of the nozzle ring, the diaphragm 7 and the bottom of the 10 casing 6, together define an inlet chamber 10.

In order to properly profile the blades 5 to provide the proper seat for the diaphragm 7, the slots S are filled with a relatively soft alloy, such as babbitt, as shown 15 in Fig. 7 and indicated there by the reference numeral 11. With the babbitt thus in place and serving as a backing during the subsequent machining operation, the blades 5 are now machined down to the profile 20 shown in Fig. 8, on which profile, diaphragm 7 is adapted to be seated and held in place by the ring 12. The babbitt is now removed and the ring is substantially complete. Holes may be drilled in the portion 3 to serve in mounting the whole in 25 the casing 6.

It will thus be seen that I have provided a one piece nozzle ring which carries integral therewith, means for supporting it directly 30 on the turbine casing, and which itself serves as a means for seating a diaphragm.

In a structure of this kind, where unusually high temperatures are met with, it will be evident that it is of distinct advantage to have the blades integral with the body of the ring, because in such a structure, there is no opportunity for erosion, due to the high velocity, hot, exhaust gases causing a weakening of separate connections between 40 the nozzle blades and nozzle ring. The portion 2 may be chamfered at the point 13 for clearance purposes.

It should also be noted that the portion 2, serves as a mounting for the nozzle ring and 45 also aids in defining the inlet chamber 10. It should also be noted that the cross-sectional area of the slots S gradually decreases from right to left of the drawing. This type of nozzle presents known advantages in 50 turbine nozzle design.

While I have shown one method of making this nozzle ring, it should be understood that this method may be modified and that the nozzle ring itself may be modified as 55 defined within the scope of the appended claims.

I claim—

1. The method of making a turbine nozzle ring, comprising cutting away a thick-walled 60 tube to leave an end portion of substantially the thickness of the original tube, and cutting slots in said end portion helical with respect to the axis of said tube.

2. The method of making a turbine nozzle ring, comprising cutting away a thick- 65

walled tube to leave an end portion of substantial thickness and a relatively thin annular portion, undercutting said end portion, and cutting slots in said end portion helical with respect to the axis of said tube. 70

3. The method of making a turbine nozzle ring, comprising cutting away a thick-walled tube to leave an end portion of substantial thickness and a relatively thin annular portion, undercutting said end portion, 75 and cutting slots in said end portion helical with respect to the axis of said tube, then bending the blades between the slots and adjacent the undercut portion toward the axis of said tube. 80

4. The method of making a turbine nozzle ring, comprising cutting away a thick-walled tube to leave an end portion of substantial thickness and a relatively thin annular portion, undercutting said end portion and cutting slots in said end portion helical with respect to the axis of said tube, then bending the blades between the slots and adjacent the undercut portion toward the axis of said tube, then filling said slots with an alloy and 90 turning the outer part of said blades down to a profile. 95

5. The method of making a turbine nozzle ring, comprising cutting helical slots in the periphery of a solid annular blank, said slots 95 being helical with respect to the axis of said ring along the edge of said blank.

6. The method of making a turbine nozzle ring, comprising undercutting a solid annular blank and cutting helical slots in the periphery of said blank, said slots being helical with respect to the axis of said ring. 100

7. The method of making a turbine nozzle ring, comprising undercutting a solid annular blank, cutting helical slots in the periphery of said blank, said slots being helical with respect to the axis of said ring, then bending toward said axis that part of the walls of the slots that overhang said undercut portion. 105

8. The method of making a turbine nozzle ring, comprising undercutting a solid annular blank, cutting helical slots in the periphery of said blank, said slots being helical with respect to the axis of said ring, then bending toward said axis that part of the walls of the slots that overhang said undercut portion, then filling the said slots with an alloy and turning down the side of the ring opposite the undercut portion to a profile. 110

9. A turbine nozzle ring, comprising an annular portion and nozzle blades integral with said annular portion, said blades gradually decreasing in height from one 125 part to the other, and a diaphragm seated on this last-mentioned part.

10. A turbine nozzle ring, comprising an annular portion and nozzle blades, helical with respect to the axis of said portion, said 130

blades gradually decreasing in height from one part to the other, and a diaphragm seated on this last-mentioned part.

11. A turbine nozzle ring, comprising an annular portion and nozzle blades, helical with respect to the axis of said portion and integral therewith, said blades gradually decreasing in height from one part to the other, and a diaphragm seated on this last-mentioned part.

12. A turbine nozzle ring, comprising an annular portion, blades defining nozzles on one part of said ring, said annular portion serving as supporting means for supporting the nozzle ring, said blades gradually decreasing in height from one part to the other, and a diaphragm seated on this last-mentioned part.

13. The combination as claimed in claim 12, the mentioned parts being made integral.

14. A turbine nozzle ring, comprising an annular portion, blades integral therewith defining slots helical with respect to the axis of said annular portion, located toward one end of the annular portion, the other end of said annular portion being adapted to be supported on the turbine casing.

15. A turbine nozzle ring, comprising an annular portion, nozzle blades defining slots helical with respect to the axis of said annular portion, said nozzle blades being undercut at one side.

16. A turbine nozzle ring, comprising an annular portion, nozzle blades defining slots

helical with respect to the axis of said annular portion, said nozzle blades being undercut at one side, said blades, adjacent said undercut portion, being curved toward the said axis.

17. The combination as claimed in claim 15, the mentioned parts being integral with one another.

18. The combination as claimed in claim 16, the mentioned parts being integral with one another.

19. A turbine nozzle ring, comprising an annular portion, blades defining slots helical with respect to the axis of said annular portion, the said blades each decreasing gradually in height from one part to the other, whereby the slots are caused to decrease in cross-sectional area from one part to another.

20. In combination with a turbine, a casing, a diaphragm arranged to divide the casing into inlet and exhaust chambers, a nozzle ring cut away at its outer edge and means to hold said diaphragm in engagement with the cut away portion of said nozzle ring.

21. In combination with a turbine, a casing, a diaphragm arranged to divide the casing into inlet and exhaust chambers, a nozzle ring, said diaphragm being arranged to engage with said nozzle ring and means to attach said nozzle ring to the casing.

In testimony whereof I affix my signature.

EARL H. SHERBONDY.
